ATTORNEY.

UNITED STATES PATENT OFFICE.

P. CHARLES GETZ, OF PHILADELPHIA, PENNSYLVANIA.

GOSSAMER-CLOAK.

SPECIFICATION forming part of Letters Patent No. 313,316, dated March 3, 1885.

Application filed February 27, 1884. (No model.)

To all whom it may concern:

Be it known that I, P. CHARLES GETZ, a citizen of the United States, residing in the city and county of Philadelphia, State of Pennsylvania, have invented a new and useful Improvement in Gossamers, which improvement is fully set forth in the following specification and accompanying drawings, in which—

Figure 1 is a view of the inner face of a gosamer embodying my invention. Fig. 2 is a section thereof in line x x , Fig. 1.

Similar letters of reference indicate corresponding parts in the two figures.

It is well known that in the garment for ladies' wear generally known as a "gossamer" the armholes are subjected to much strain when the arms of the wearer are inserted and removed and the garment is in service, hence the liability of said armholes to be torn and separated, especially at top and bottom, and the gossamer is accordingly injured.

My invention consists in re-enforcing a gosamer in such manner that the armholes are re-enforced and strengthened and enabled to endure the strain to which they are subjected.

Referring to the drawings, A represents the body of a garment of the order of a gossamer, which, excepting the features of my invention, is of well-known construction.

B represents one of the armholes of the garment, and C the facing or sleeve-piece thereof usual in such cases.

At the top and bottom walls of the armhole,

on the inside thereof, are patches D, and on the inside of the gossamer, at places coinciding with the corners of the facing C, are patches E. The patches D are secured to the walls of the armholes by stitches passed through the patches and walls, and the patches E are secured to the material of the gossamer by stitches passed through said material and facing C, it being seen that the material of the gossamer at the upper and lower terminations of the armholes and the connections of the facings with said material are re-enforced, thus increasing the strength of the armholes and facings and rendering the gossamer more serviceable and durable than heretofore.

The re-enforcing patches may be made of rubber or material similar to the gossamer, leather, &c.

Having thus described my invention, what I claim as new, and desire to secure by Letters Patent, is—

A gossamer having armholes B and sleeve-pieces C therefor provided with patches D, connected with the body and walls of the upper and lower terminations of the armholes, and patches E, connected with the body and sleeve-pieces at places coincident with the corners of said pieces, substantially as and for the purpose set forth.

P. CHAS. GETZ.
